US0D1058517S

(12) **United States Design Patent** (10) **Patent No.:** **US D1,058,517 S**
(45) **Date of Patent:** ** *Jan. 21, 2025

(54) **BATTERY CABLE ASSEMBLY**

(71) Applicant: **The Noco Company**, Glenwillow, OH (US)

(72) Inventors: **Derek Michael Underhill**, Tempe, AZ (US); **Jonathan Lewis Nook**, Gates Mills, OH (US)

(73) Assignee: **The Noco Company**, Glenwillow, OH (US)

(*) Notice: This patent is subject to a terminal disclaimer.

(**) Term: **15 Years**

(21) Appl. No.: **29/892,898**

(22) Filed: **May 23, 2023**

Related U.S. Application Data

(63) Continuation of application No. 29/761,829, filed on Dec. 11, 2020, now Pat. No. Des. 991,185.

(57) **CLAIM**

The ornamental design for a battery cable assembly, as shown and described.

DESCRIPTION

FIG. 1 is a perspective view of a new design for a battery cable assembly;

FIG. 2 is a top plan view thereof; and,

FIG. 3 is an enlarged perspective view of a new design for a battery cable assembly, showing battery clamps connecting to the battery cable assembly.

1 Claim, 3 Drawing Sheets
